E. A. RITCHIEY

PERFORATOR

Filed Oct. 19, 1925

UNITED STATES PATENT OFFICE.

EDWARD A. RITCHIEY, OF HUNTINGTON BEACH, CALIFORNIA.

PERFORATOR.

Application filed October 19, 1925. Serial No. 63,324.

This invention has to do with a perforator and has particular reference to a perforator intended to be operated in a well to perforate casing, or the like, located therein.

5 It is an object of this invention to provide a perforator which will form perforations in a casing without ripping or distorting the casing.

Another object of this invention is to provide 10 a perforator which is operable to form a plurality of perforations simultaneously.

Another object of this invention is to provide 15 a perforator in which the cutting parts are comparatively small and simple and are mounted so that they are durable and effective.

It is a further object of this invention to provide 20 a perforator in which the actuating member can overtravel after the cutters have been actuated without affecting the cutters.

It is another object of this invention to provide 25 a perforator in which the parts are related so that they will not become clogged with sand or mud but will always remain in proper operating condition.

The various objects and features of my invention will be best and more fully understood from the following detailed description 30 of a typical form of the invention through which description reference is had in the accompanying drawings in which:

Fig. 1 is a longitudinal detailed sectional view of the perforator provided by this invention showing it being run into a well casing.

Fig. 2 is a sectional view of the perforator showing it in an actuated position within a 35 casing.

Fig. 3 is an enlarged view of a portion of Fig. 2, and

Fig. 4 is an enlarged detailed transverse sectional view of the perforator taken as indicated by line 4—4 on Fig. 1.

The device provided by this invention is 45 intended to form perforations in a casing C, or the like, located in a well. The perforator includes, generally, a body 10, cutters 11 carried by the body, an actuating member or stem 12 in connection with the body to actuate the cutters, and means 13 operable to hold the body against longitudinal movement in the casing during actuation of the cutters.

The body 10 is an elongate member round 50 in cross sectional configuration and having a central longitudinal opening 15. The lower

end portion 15^a of the opening in the body is enlarged to carry certain parts of the operating stem as to be hereinafter described.

The cutters 11 are in the form of punches 60 slidably carried in radially disposed openings 16 in the body. The openings 16 are in the lower part of the body so that they open into the enlarged portion 15^a of the opening 65 in the body.

In accordance with my invention there is preferably a plurality of cutters, arranged symmetrically around the central longitudinal axis of the device and the cutters are preferably located in a common horizontal plane. 70 In the particular perforator shown in the drawings there are four cutters 11 located 90 degrees apart around the body in a common horizontal plane. With this construction the device will operate to form four perforations in a single operation. 75

The cutters 11 may be, and preferably are, all of the same size, and construction. In the preferred construction the outer end portion 20 of each cutter is shaped and finished 80 as a cutting part adapted to penetrate or cut through the casing C. In the construction shown in the drawings the outer end portions of the cutters are somewhat reduced to form the cutting parts 20. Each cutter is 85 provided in its inner end, or, within the opening 15^a of the body with a head 21 connected with the main portion of the cutter through a neck 22. The heads 21 of the cutters serve as parts by or through which the 90 cutters are connected with the operating stem as will be hereinafter described.

The operating stem is slidably carried in the opening 15 so that its upper end is above the body and its lower end within the portion 15^a of the opening in the body. The entire device is adapted to be connected with an operating element such as a string of percussion tools or tubing. The upper end of the stem may be provided with a suitable sub or coupling 30, adapted to connect the stem with the lower end of a string of percussion tools, or tubing. The lower end portion 31 of the operating stem is wedge shaped or tapered and is provided with guide-ways 32, adapted to carry the heads 21 of the cutters. The lower end of the stem is downwardly tapered, or convergent, and is provided with as many guide-ways as there are cutters. The guide-ways are shaped as shown in Fig. 4 so that they hold the heads 100 of the cutters causing the cutters to move 105 110

radially in the openings 16 upon movement of the stem longitudinally with reference to the body. When the parts are related so that the heads of the cutters are at the lower 5 or small end of the tapered part 31, the cutters are retracted or in the position where they do not project beyond the body 10. As the tapered part 31 is moved downwardly with reference to the body the cutters are 10 moved outwardly until the heads of the cutters are at the upper or large end of the tapered part at which time the cutters are in an actuated or out position where they project far enough from the body to extend 15 through the casing C. In accordance with my invention the guide-ways 32 are continued in, or on, the operating stem for a considerable distance upward from the tapered part 31 so that the operating stem can continue to move downwardly, or over-travel, after the cutters are fully actuated without further actuating or forcing the cutters downwardly in a manner to rip the casing. 20 In the construction shown in the drawings 25 the lower end portion of the stem in which the guide-ways are formed, is somewhat larger in diameter than the rest of the stem, in fact, it is made to work in the enlarged portion 15^a of the opening of the body and 30 co-operates with the shoulder 40, formed in the body between the opening 15 and portion 15^a, to limit the upward movement of the stem with reference to the body. The 35 downward movement of the stem with reference to the body may be limited by the coupling 30 engaging the upper end of the body.

It will be obvious that the various parts 40 may be proportioned and related so that the desired relative movement can be obtained between the various parts.

The means 18, provided for holding the body against longitudinal movement in the casing during operation of the cutters, may 45 include slips 50 adapted to be actuated to grip the casing C, friction means or springs 51 adapted to engage the casing to actuate the slips, and a suitable catch device for controlling the springs 51. The slips 50 are carried on a suitable tapered part 52 at the upper end of the body and are provided with roughened faces 53 adapted to grip the interior of the casing C. The springs 51 are leaf-springs of the type employed on tail 55 pieces and are carried between upper and lower collars 54 and 55, respectively, slidably carried on a reduced part 56 of the body below the tapered part 52. The upper collar 54 engages, or, is connected with the 60 slips. The springs 51 are bowed outwardly to normally frictionally grip the exterior of the casing. The means for controlling the springs may include a spring latch 58 carried by the lower collar 55 to 65 co-operate with a catch 59 on the body.

The catch 59 is adapted to hold the latch 58 when the springs 51 are in a down position with reference to the body in which position the slips are down or inactuated. The latch 58 is in a form of a 70 leaf-spring normally tending to assume a position such as is shown in Fig. 5, and therefore must be sprung or forced inwardly in order to engage under the catch 59. When the latch is held by the catch, the slips are 75 down or inactuated and the tool can be easily moved downwardly in the casing. To release the springs 51 so that they will actuate the slips 50, the device is moved upwardly in the casing sufficient to allow the latch to 80 become released from the catch whereupon the downward movement of the device, or of the tubing connected with the operating stem 12, will cause movement of the body with reference to the springs 51 causing actuation of the slips 50. When the slips have 85 been actuated the body can not move downwardly in the casing so continued downward movement of the drill pipe will move the stem downwardly with reference to the body 90 in a manner to actuate the cutters.

I provide means for holding the operating stem in an up position with reference to the body while the device is being run into the casing C this means may include a shear pin 95 60 connecting the body 10 and stem 12 so that the stem will remain up with reference to the body during the running of the tool into the casing but will shear off or fail, upon the stem being forced or jarred downwardly after the slips have gripped the casing. 100

From the foregoing description of the device it is believed that the manner of operation will be apparent; the tool is run into 105 the casing C with the parts in the position shown in Fig. 1; the stem 12 being held in the up position with reference to the body 10 by the shear pin 60 and the friction spring 51 being held down or in a position 110 where the slips are unactuated by the co-operation of the latch 58 and catch 59. When the tool has been moved downwardly to the desired point of the casing the latch 58 is released from the catch 59 by a slight 115 upward movement of the tubing carrying the tool. The springs 51 being in friction engagement with the casing hold the latch 58 so that upward movement of the stem causes the catch 59 to move upward relative to the latch and thus release it. When the latch is released and the slips set, the tubing may be lowered to shear off the pin 60 so that the stem can operate with reference to the body. 120 Downward movement of the stem will then cause actuation of the cutters. The cutters are operated simultaneously and being arranged symmetrically within the casing operate to punch through it without distortion. 125 When the cutters have been actuated the 130

stem is moved upwardly so that the cutters are withdrawn and the body moved upwardly in the casing to another position where the operation can be repeated.

Having described only a typical preferred form of my invention I do not wish to limit myself to the specific details set forth, but wish to reserve to myself any changes or variations that may appear to those skilled 10 in the art or fall within the scope of the following claim.

Having described my invention, I claim:
A perforator including a body, a cutter carried by the body, an operating member 15 for the cutter, slips carried by the body oper-

able to set the body in a casing, and control means for the slips, including a spring normally frictionally engaging the casing and a catch device controlling the movement between the spring and body, the catch device 20 comprising a spring latch operable with the spring and a catch on the body to hold the latch during downward movement of the perforator and to release the latch upon upward movement of the body.

In witness that I claim the foregoing I have hereunto subscribed my name this 17th day of September, 1925.

EDWARD A. RITCHHEY.
